DRIER FOR FIBER BOARD

Application filed August 28, 1929. Serial No. 389,175.

The present invention relates to driers for fiber board and the like. Such driers are used for compacting sheets of wet fiber, by heat and pressure, into more or less dense, coherent board. My invention affords various practical advantages, such as large capacity of the drier, thorough and efficient removal of water, convenient, rapid and economical operation.

How these and other advantages can be realized through my invention will appear from my description hereinafter of selected and preferred embodiments.

In the drawings, Fig. I is a side elevation of an apparatus conveniently embodying my invention.

Fig. II is a similar view at right angles to Fig. I.

Fig. III is a plan view of the apparatus.

Fig. IV is a fragmentary side view of the supporting chains for the drier plates, similar to that afforded by Fig. II but on a larger scale.

Fig. V is a view of the chains at right angles to Fig. IV.

Fig. VI is a fragmentary view of the chains corresponding to Fig. V, but with the drier plates closed against one another.

Fig. VII is a fragmentary side view of mechanism for separating the drier plates, with certain parts in vertical midsection.

Fig. VIII is a similar view of certain parts in Fig. VII, showing some of them in a different position.

Fig. IX is a plan view of part of the mechanism shown in Fig. VIII.

The drier shown in Figs. I and II comprises a stack of plates 11 between which the sheets of wet fiber S are compacted and dried, sheets and plates in alternation. Thus a great many sheets can be dried concurrently. The wet, raw sheets may be introduced into the stack one by one, as they are manufactured, instead of in batches, a dried or "cured" sheet being discharged when a raw sheet is introduced to take its place. Thus drying goes on continuously, notwithstanding the continual discharging and recharging; and there is no period during which all plates remain closed and the activity of the

sheet-producing machinery must be suspended (or its product accumulated or diverted to another drier),—or, at any rate, this period is reduced to a minimum.

As shown in Figs. I and II, the plates 11 are provided with spacing means 21 in the form of projections at their upper sides, which determines the thickness to which raw sheets S are compressed in the drier.

The plates 11 are flexibly interconnected and suspended by chains of links 22 pivoted to lugs 23 on the edges of the plates. As shown in Figs. I and II, there are two pairs of these chains 22, attached at their upper ends to lugs 24 on a frame-work of I-beams 25 at the top of the machine. Each of the chains 22 is flexible between successive plates 11 connected by it, so as to allow them to approach one another by flexure of the chain. In the present instance (see Fig. IV), the two chains 22 of each pair are connected to alternate plates 11 only: i. e., one chain to the first, third, and fifth plates, etc., and the other chain to the second, fourth, and sixth plates, etc. This allows the chains to be made with longer single links.

The chains 22 resemble sprocket chains in construction, each of them comprising two sets of overlapping flat links 26, 27 interconnected by pivots 28. Alternate pivots 28 extend through the lugs 23 and the other pivots 28 are provided with spacing means 29. Square stop bars 30 extend between corresponding outside links 27 at their middle, to engage shoulders 31 (see Fig. V) on the lower ends of the inside links 26. Thus the interconnected links 26, 27 can never straighten out completely to a dead center, and can only flex outward from the plates 11: i. e., they can never come between the plates 11 and block the plates from coming together properly. When the plates 11 are closed together, the stop bars 30 are accommodated in notches 32 in the edges of the links 26, as shown in Fig. VI.

When the chains 22 hang free, as at U in the upper part of Figs. I and II, the plates 11 are separated further than the thickness of a wet, raw sheet S, thus permitting the inter-spaces to be charged and the sheets that have

been dried to be discharged. As the plate interspaces are charged, however, the corresponding plates 11 are brought together upon the wet sheets S, to compress, heat, and dry them. As here shown, this is done by successively lowering the plates 11 on a bottom support or cradle 33, in a pile L. This is done by lowering the chain-supporting overhead structure 25, which rests on the heads of plungers 35 that work in vertical hydraulic cylinders 36 fixed to the machine base 37,—water being concurrently admitted to the cylinders 36 or exhausted from them through common pipe connections 38. To assure coincident movement of the plungers 35 and thus prevent the frame 25 from "cocking", interconnected gears 39 are provided at the corners of the frame, meshing with racks on uprights 40 fixed to the base 37. The gears 39 at each side of the frame are mounted on a common shaft 41, and the two shafts 41 are interconnected by transverse shafts 42 and sets of bevel gears 43.

It is of advantage to introduce the wet sheets S, and to discharge the dried or "cured" sheets, always at one constant charging and discharging level; and for this purpose, I provide for shifting the whole stack of plates 11 vertically, so as to present all of its plate intervals at the one level. As shown in Figs. I and II, provision is made for raising and lowering the bottom support 33 by means of hydraulic "jacks" comprising plungers 44 that work in cylinders 46 mounted on the base 37,—water being concurrently admitted to the cylinders 46 or exhausted from them through common pipe connections 48. Each time the overhead support 25 is lowered to transfer a plate 11 from the upper suspended group U to the lower piled up group L, the bottom support 33 is also lowered a distance equal to the thickness of a plate 11, including its spacing means 21. Thus the top plate 11 of the lower group L is always at substantially a constant charging or loading level,—i. e., the level shown in Figs. I and II,—and the stack of plates as a whole is lowered as its plate intervals are charged and closed.

To facilitate the charging of the drier plate stack, provision may be made for augmenting the plate interval at the charging or loading level, so as to afford more space. As shown in Figs. I and II, this is done by lifting the lowermost plate 11a of the upper group U toward or against the plate 11b next above it,—an operation permitted by the fact that each chain 22 is connected to alternate plates 11 only. As shown, the lifting means (Figs. I—III and VII—IX) is provided in duplicate at the two ends of the machine, so as to lift the plates 11 evenly. At each side, there are two lifting arms 50, 50 fixed to a shaft 51 mounted in bearing brackets 52 on a supporting structure 53 attached to the uprights 40, and each plate 11 has a correspond-

ing pair of lifting lugs 55 on its edge. A crank arm 56 is fixed on the shaft 51, and connected by double links or pitmen 57 to the cross-head 58 of a hydraulic motor 60.

As shown in Fig. VII, the motor 60 comprises upper and lower hydraulic cylinders 62, 63, inter-connected by guide rods 64 which extend through guide openings in the cross-head 58, to which are attached a small plunger 65 for the lower cylinder 63 and a large plunger 66 for the upper cylinder 62. As shown, the upper cylinder 62 is attached to the supporting structure 53, and the lower cylinder 63 to another supporting structure 67 attached to the uprights 40. The lower cylinder 63 is constantly supplied with water under pressure by a pipe connection 68, while water under pressure is admitted to the upper cylinder 62, or exhausted therefrom, through a pipe connection 69 with a control valve 70. Thus the cross-head 58 is kept raised, and the arms 50, 50 depressed (as shown in full lines in Fig. VII) except when pressure is admitted to the (larger) upper cylinder 62 to lower the cross-head and raise the arms 50, 50.

Preferably, the arms 50, 50 do not directly engage the plate lugs 55, 55, but are each provided with a latch finger 71 for this purpose, pivoted on the arm at 72 and yieldingly held in the outstanding, active position of Fig. VII by a helical spring 73 connected to the latch and to the bearing bracket 52,—this active position of the latch being determined by a stop shoulder 74 on the latch and a corresponding stop lug 75 on the arm. The latch 71 acts as part of the arm 50 to raise the plates 11, but yields as shown in Fig. VII to allow a plate lug 55 to pass the arm if the plates 11 should be lifted too far at the wrong time, by an improvised upward movement of the cradle 33.

As shown in Figs. I and II, the lifting devices or arms 50 at opposite ends of the machine are interconnected to assure action in unison and even lifting of the plates 11. For this purpose, each cross-head 58 is connected by duplicate links or pitmen 76 to one arm of a bell-crank lever 77 fulcrumed at 78 on the base 37, and the other arms of the two bell-crank levers 77, 77 are interconnected by a link rod or pitman 79.

The wet sheets S may be introduced by a reciprocating loader 82, and dried sheets S pushed out by this loader 82 to make way for the wet sheets. The loader 82 may be of any suitable construction, such as that described in a pending application, Serial No. 307,839, filed September 24, 1928, by Daniel Manson Sutherland, Jr., assignee of this application. For present purposes, it may be sufficiently described as comprising a carriage 83 with wheels or rollers 84 travelling to and fro on stationary rails 85, and provided with a travelling apron 86 formed by the top run of an endless belt guided, driven, and supported

by rolls 87, and also a sloping supplemental apron belt 88 in front of the main belt, guided and driven by rolls 89. This sloping belt 88 always travels with the main belt 86 at the same surface speed, and serves to support the wet sheet S in its transition from the main belt 86 to the plates 11.

To introduce a sheet S on the loader 82 into the stack, the loader 82 moves to the right (Fig. 1) until the sheet S is in substantially its intended position relative to the plate 11 beneath it, the aprons 86, 88 remaining stationary relative to the carriage. During this movement, the loader engages the edge of a previously dried sheet S resting on the plate 11, and pushes this sheet out to the right, on to the discharge rolls 90. The loader 82 then returns back to the left clear of the stack, while its aprons 86, 88 travel to the right relative to the carriage 83 at a linear speed just equal to that of the carriage toward the left; and thus the sheet S is let down and deposited on the plate 11 substantially without moving either way relative to the latter.

The plates 11 may be heated by any suitable or preferred means, electrical or otherwise.

The general operation of the apparatus may be summarized as follows:

Initially, the chains 22 hang free, with the stack of plates 11 all fully separated or expanded, and the lowermost plate 11 resting on the cradle 33 with its top surface just below the loader 82. The plate 11 next the bottom is raised against that just above it, by the devices 50, 50 thus augmenting the normal interval between the plates, and the loader 82 enters and deposits a wet sheet S on the bottom plate, and withdraws. The devices 50, 50 are lowered, releasing the plate 11 that has been resting on them; the cradle 33 is lowered a distance equal to the thickness of a plate (including the spacing means 21); and the supporting structure 25 is lowered a distance equal to the thickness of a plate plus the normal interval between the plates (when hanging free). Accordingly, the plate 11 next above the bottom is transferred from the upper suspended group U to the lower stacked group L and the lowermost plate 50 interval is closed on the sheet S,—thus squeezing and compressing the sheet S as much as permitted by the spacing means 21.

This cycle of operations is repeated over and over again until all the plate intervals have been charged and closed.

The fully charged stack of plates 11 is allowed to remain closed until all the sheets S in it have had time to dry or "cure" properly, and is then opened up or expanded completely by raising the structure 25. Thereupon all the dried sheets S may be expelled or withdrawn in any suitable manner, leaving the stack empty and ready for recharging. Or, instead of being thus expelled before the stack is recharged, the dried sheets S may be

pushed out one by one by the loader 82 as it enters the plate intervals with wet sheets S for the next charging of the apparatus,—always, of course, at the one constant charging level,—as already mentioned above.

Having thus described my invention, I claim:

1. An apparatus of the character described comprising a multiplicity of plates suspended at an interval one above another, means for introducing raw sheets into the spaces between adjacent plates, means for lifting against one another the plates whose intervals have been thus charged, and means for raising and lowering the suspended plates above the charged pile of plates.

2. An apparatus of the character described comprising a multiplicity of interconnected plates suspended at an interval one above another, means for lifting the plates from beneath into a pile, means for lifting the plate just above the pile toward the plate above it, so as to increase the space between the plate thus lifted and the top of the pile, and means for introducing a raw sheet into the thus augmented space.

3. An apparatus of the character described comprising a stack or series of plates with means for suspending them at an interval one above another, means for advancing raw sheets to the stack at substantially a constant loading level, means for supporting the plates below the loading level piled on one another, and for raising and lowering the pile, and means for raising and lowering the suspended plates above the pile.

4. An apparatus of the character described comprising a stack or series of plates with means for suspending them at an interval one above another, means for advancing raw sheets to the stack at substantially a constant loading level, means for supporting the plates below the loading level piled on one another, and for raising and lowering the pile, means for raising and lowering the suspended plates above the pile, and means for lifting the plate above the pile toward that above it, so as to increase the plate interval at the loading level.

5. An apparatus of the character described comprising an overhead structure and a multiplicity of interconnected plates suspended therefrom at an interval one above another, means for raising and lowering said overhead structure and the plates hanging therefrom, a cradle for lifting and supporting the plates in a pile and means for raising and lowering said cradle, and means for introducing a raw sheet into the space between the top of the pile and the plate hanging above it.

6. An apparatus of the character described comprising an overhead structure and a multiplicity of interconnected plates suspended therefrom at an interval one above another, means for raising and lowering said overhead

structure and the plates hanging therefrom, a cradle for lifting and supporting the plates in a pile and means for raising and lowering said cradle, means for lifting the plate hanging just above the pile toward the plate above it, so as to increase the space between the plate thus lifted and the top of the pile, and means for introducing a raw sheet into the thus augmented space.

10. 7. An apparatus of the character described comprising a stack or multiplicity of plates alternately interconnected and thereby suspended at an interval one above another in independent series, means for temporarily lifting each plate toward that above it and thus increasing its distance above that beneath it, and means for introducing a raw sheet into the thus augmented space.

8. An apparatus of the character described comprising a stack of multiplicity of plates alternately interconnected and thereby suspended at an interval one above another in independent series, means for advancing raw sheets to the stack at substantially a constant loading level, means for supporting the plates below the loading level piled on one another, and for raising and lowering the pile, means for raising and lowering the suspended plates above the pile, and means for lifting the plate above the pile toward that above it, so as to increase the plate interval at the loading level.

9. An apparatus of the character described comprising a stack or multiplicity of plates alternately interconnected and thereby suspended at an interval one above another in independent series.

10. An apparatus of the character described comprising a stack or multiplicity of plates, and chains for supporting the plates at an interval one above another in independent series, the plates being attached in alternation to different sets of chains.

11. An apparatus of the character described comprising a stack or multiplicity of plates, folding links interconnecting alternate plates and thereby suspending the plates at an interval one above another in independent series, means for lifting the plates from beneath into a pile, and means for preventing the links from flexing inward between the plates.

In testimony whereof, I have hereunto signed my name at Trenton, New Jersey, this 26th day of August, 1929.

FRANCIS S. FARLEY.
